UNITED STATES PATENT OFFICE.

JOSEPH M. NEENAN AND JAMES P. WEAVER, OF CHARLESTON, WEST VIRGINIA, AS
SIGNORS TO THE LIBBEY-OWENS SHEET GLASS COMPANY, OF TOLEDO, OHIO, A COR-
PORATION OF OHIO.

WIDTH-MAINTAINING MEANS FOR SHEET-GLASS APPARATUS.

Application filed December 9, 1926. Serial No. 153,510.

This invention relates to an improved method and apparatus for producing sheet glass and more particularly for maintaining the said sheet to width.

5 An important object of the invention is to provide, in sheet glass apparatus, means for containing a mass of molten glass, means for drawing a sheet therefrom, and improved means engaging the edges of the sheet to prevent narrowing thereof.

Another object of the invention is to provide, in sheet glass apparatus, means for continuously drawing a sheet from a mass of molten glass, and means engaging the edges 15 of the sheet to prevent narrowing thereof in combination with means for directing a current of air onto the sheet edges before they contact with said edge engaging means.

Other objects and advantages of the invention will become more apparent during the course of the following description when taken in connection with the accompanying drawings.

In the drawing forming a part of this application and wherein like numerals are employed to designate like parts throughout the same,

Fig. 1 is a transverse sectional view of sheet glass drawing apparatus showing associated therewith improved width maintaining means constructed in accordance with the present invention,

Fig. 2 is an enlarged top plan showing one of the improved width maintaining devices in position,

Fig. 3 is an inner edge elevation of one of the improved width maintaining devices, and

Fig. 4 is a detail perspective view of one of the said width maintaining devices.

40 The present invention relates particularly to the formation of a flat sheet of glass wherein the sheet is continuously drawn from a mass of molten glass. The type of apparatus set forth in the drawings is similar to the 45 construction disclosed in the Colburn Patent No. 1,248,809 granted Dec. 4, 1917 wherein is provided a draw pot 5 containing a mass of molten glass 6, and a sheet 7 is drawn from the said mass initially in the vertical plane for 50 a short distance after which it is deflected while still in a semi-plastic condition although substantially set in its final sheet form, over a bending member 8 into the horizontal plane.

The glass is then run through a combined flattening and drawing mechanism into an 55 annealing leir where it is gradually reduced to room temperature as is well known in the art.

In drawing a sheet of glass vertically in this manner, it is necessary to provide some 60 form of means having an action on said sheet adapted to prevent narrowing thereof. In accordance with the Colburn patent above set forth, a pair of rotatable knurled rollers are provided at both edges and on opposite sides 65 of the sheet to form an edge thereon sufficiently viscous to prevent narrowing of the sheet to an appreciable extent. It is an aim of the present invention to substitute for these knurled rollers, improved width maintaining members to obviate the necessity for the driving mechanism formerly employed and to also cut down the amount of waste that has heretofore been had.

In accordance with the present invention, 75 there is provided at each edge of the sheet 7 and preferably closely adjacent the base or meniscus 9, a pair of preferably hollow stationary members 10 and 11 which engage the opposite sides of said sheet. These members, 80 which may be formed of Monel or any other desirable and suitable non-corrosive metal alloy, are carried by the inner ends of supporting arms 12 and 13 and a portion of the adjacent faces thereof are slightly cut away 85 to form a slot 14, terminating at its inner end in an enlarged and preferably circular opening 16. The sheet edge is adapted to

be drawn upwardly through the slot 14 and the opening 15 and it will be noted upon reference to Fig. 2 that the sheet edge contacts only with the walls of the opening 15 and does not contact with the walls of the slot 14.

As will be more fully pointed out later, the members 10 and 11 are internally cooled even 90 though the walls of the slots 14 do not actually contact with the sheet. As is shown, they are arranged relatively close to said sheet edges in a manner that they will absorb heat from said sheet. Obviously, this acts to 95 strengthen the edges, thereby reducing the tendency of the sheet to narrow. In this way, a relatively wider sheet can be drawn from a given width of pot for the reason that it is possible to cap closer to the edge of the sheet. 100 Furthermore, by the use of this invention

it is possible to do away with the formation of such a roughened edge on the sheet as now results from the use of the knurled rollers.

The outer ends of the supporting arms 12 and 13 are mounted upon a base 16 slideable within a guide-way 17 so that the width maintaining members 10 and 11 may be moved towards and away from the sheet as desired. The base 16 is rigidly secured in the desired 10 position by means of set screws or the like 18.

One way of mounting the supporting arms 12 and 13 is to have one arm stationary and the other movable in order that the said width maintaining members 10 and 11 may 15 be forced inwardly towards one another. As shown, the arm 13 is stationary while the arm 12 is pivotally mounted on the base 16 by means of a pivot pin 19. A spring 20 acts to normally urge the arm 12 about its 20 pivot 19 so as to move the width maintaining members 10 and 11 into engagement with the sheet edge but this spring is of course sufficiently weak or resilient to permit the drawing of the sheet between the said width 25 maintaining members.

In order to prevent the width maintaining members 10 and 11 from overheating, pipes 21 are carried by the supporting arms 11 and 12 to permit the continuous circulation of a suitable cooling medium, such as 30 relatively cool water, through the said members. This cooling medium enters through the pipe 22 and after passing through the said width maintainers passes outwardly 35 through pipe 23.

One of the most important features of the present invention is the provision of means for directing a current of air onto the sheet edges before they contact with the width 40 maintaining members 10 and 11 and, as shown, suitable pipes or the like 25 may be provided for accomplishing this purpose. By the use of this air, a relatively heavy edge will be formed on the sheet below the edge 45 engaging means and as stated, the sheet will pass between the said members without actual contact except in the circular opening 15. The lower faces of the members 10 and 11 are curved downwardly and outwardly as 50 indicated at 24 in order that the sheet will not contact therewith as it is being drawn and so that a relatively wider sheet can be drawn from a given width of pot due to the small area of contact between the sheet and 55 width maintaining members.

The operation of the machine with these width maintaining devices will be slightly different than with the knurled rollers described above. The edge of the glass sheet 60 drawn upwardly will be pulled through the slot 14 and opening 15 and because of the inherent tendency of molten glass, a certain amount of frictional resistance will be had between the moving glass and the members. 65 This frictional retardation causes a lowering

of the temperature of the glass which is further accelerated by means of the cooling medium and the current of air being directed on the edges of the sheet. This cooling is not so severe that the glass becomes set but 70 it is of such a nature that the edges of the glass will be comparatively viscous to the main body of the glass, thus being sufficiently strong to prevent the glass sheet from narrowing at its base. 75

While the present invention has been described hereinabove in connection with one particular type of process, yet it is to be understood that its use is not to be restricted to any one specific form of sheet glass apparatus inasmuch as it may be used just as satisfactorily in other types of processes. 80

It is to be understood that the form of the invention herewith shown and described is to be taken as the preferred embodiment of 85 the same, and that various changes in the shape, size and arrangement of parts may be resorted to without departing from the spirit of the invention or the scope of the subjoined claims. 90

We claim:

1. In sheet glass apparatus, means for drawing a sheet from a mass of molten glass, including width maintaining means, and means for directing a jet of air onto the edges 95 of the sheet before the said edges contact with said width maintaining means.

2. In sheet glass apparatus, means for drawing a sheet from a mass of molten glass, including stationary width maintaining 100 members engaging the opposite edges of the sheet being drawn, and means for playing a current of air on the edges of the sheet before the said sheet edges contact with said width maintaining members. 105

3. In sheet glass apparatus, means for drawing a sheet from a mass of molten glass, including stationary width maintaining members engaging opposite edges of the sheet being drawn, means for directing a jet of air 110 on the edges of the sheet before they contact with said width maintaining members, and means for circulating a cooling medium through said width maintaining members. 115

4. In sheet glass apparatus, means for drawing a sheet from a mass of molten glass, and a pair of width maintaining members positioned at each edge of the sheet being drawn, each pair of members being arranged to form a slot for receiving the sheet edge and 120 each slot terminating at its inner end in an enlarged opening, the distance between the walls of the slot being greater than the thickness of the glass sheet being formed, whereby the sheet contacts in the enlarged opening 125 only.

5. In sheet glass apparatus, means for drawing a sheet from a mass of molten glass, a pair of width maintaining members positioned at each edge of the sheet being drawn, 130

each pair of members being arranged to form a slot for receiving the sheet edge and each slot terminating at its inner end in an enlarged opening, and means for directing a current of air on the sheet edge before it contacts with said width maintaining members.

6. In sheet glass apparatus, means for drawing a sheet from a mass of molten glass, a pair of width maintaining members positioned at each edge of the sheet being drawn, each pair of members being arranged to form a slot terminating at its inner end in an enlarged opening, the sheet edge being drawn through said slot and opening and contacting only with the walls of said opening, and means for playing a jet of air on the sheet edge before it contacts with the width maintaining members.

7. In sheet glass apparatus, means for drawing a sheet from a mass of molten glass, and a pair of non-rotatable width maintaining members arranged at each edge of the sheet and positioned closely adjacent the base thereof, the width maintaining members comprising a pair being adjustable with respect to each other, said members being provided with faces curving away from said sheet to prevent contact between said faces and the sheet or the molten glass from which the sheet is drawn.

8. In sheet glass apparatus, means for drawing a sheet from a mass of molten glass, and a pair of width maintaining members positioned at each edge of the sheet being drawn, each pair of members being arranged

to form a slot for receiving the sheet edge and each slot terminating at its inner end in an enlarged opening, the lower faces of said members being curved to prevent the sheet from being drawn into contact therewith, said sheet edges contacting in the enlarged openings of the width maintaining members.

9. The method of forming a continuous sheet of glass which consists in drawing a sheet from a mass of molten glass, directing a current of air on the edges of the sheet, and subsequently drawing the said sheet edges into contact with sheet width maintaining means.

10. In sheet glass apparatus, a receptacle containing a mass of molten glass, means for drawing a sheet therefrom, a pair of non-rotatable members arranged at each edge of the sheet, portions of said members contacting with the sheet edges, means for normally urging the pair of members at each edge toward each other, and means for directing a current of air on the sheet edges beneath said non-rotatable members.

11. The method of producing sheet glass consisting in drawing a sheet from a mass of molten glass, directing a current of air on the edges of the sheet, and subsequently moving the sheet edges in contact with stationary frictional surfaces.

Signed at Charleston in the county of Kanawha and State of West Virginia, this 2nd day of December, 1926.

JOSEPH M. NEENAN.
